(57) **CLAIM**

I claim the ornamental design for a bottle organizer, as shown and described.

DESCRIPTION

FIG. 1 is a top perspective view of a bottle organizer, showing my new design.

FIG. 2 is a front elevational view of the bottle organizer.

FIG. 3 is a rear elevational view of the bottle organizer.

FIG. 4 is a left side elevational view of the bottle organizer.

FIG. 5 is a right side elevational view of the bottle organizer.

FIG. 6 is a top plan view of the bottle organizer; and,

FIG. 7 is a bottom plan view of the bottle organizer.

The broken lines depict portions of the article that form no part of the claimed design.
